UNITED STATES PATENT OFFICE.

HERSCHEL A. PRICKETT, OF COLUMBIA CITY, INDIANA.

BREECHING-STAY FOR HARNESS.

SPECIFICATION forming part of Letters Patent No. 328,901, dated October 20, 1885.

Application filed December 6, 1884. Serial No. 149,678. (No model.)

To all whom it may concern:

Be it known that I, HERSCHEL A. PRICKETT, of Columbia City, in the county of Whitley and State of Indiana, have invented certain new and useful Improvements in Breeching-Stays for Harness; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved breeching-stay for harness, showing the same applied in position for operation. Fig. 2 is a longitudinal vertical sectional view of the same, and Fig. 3 is vertical sectional view taken on the line *xx* in Fig. 2.

The same letters refer to the same parts in all the figures.

This invention relates to breeching-strokes for harness; and it has for its object to provide a device of this class which shall possess superior advantages in point of simplicity, durability, neatness of appearance, facility of attachment, and general efficiency.

With these ends in view the invention consists in the improved construction and arrangement of parts, which will be hereinafter fully described, and particularly pointed out in the claim.

In the drawings hereto annexed, A designates the breeching-strap, and B the stay, which is composed of two suitably-curved wire or metallic rods, C C, covered in the usual manner with leather, as at D.

E is a buckle-plate, the lower corners of which are provided with diagonal downwardly-extending sockets F F, the inner ends of which are screw-threaded to receive the upper ends of the rods C C, and the outer ends of which are enlarged, as shown at O, to receive the ends of the leather covering P of the said rods.

G is a D-shaped link, the straight bar of which receives the front end of the breeching layer, thus insuring perfect flexibility without regard to the remaining portion of the stay.

The said link is provided with an upwardly-projecting screw-threaded socket, H, which

receives the front end of one of the rods C, and the outer end of which socket is also enlarged, as shown at O, to receive the end of the leather covering P of said rod. The rear end of the other rod C, with its leather covering, is similarly inserted into a screw-threaded socket, I, having enlarged outer end, O, and extending upwardly from a small D-plate, J, having a leather filling and secured by stitching in the usual manner to the breeching-strap.

The operation and advantages of this invention will be readily understood from the foregoing description, taken in connection with the drawings hereto annexed.

The construction is simple and inexpensive.

The tug and buckle usually employed for connecting the breeching-stay to the hip-strap are dispensed with, inasmuch as the buckle-plate E enables the device to be adjustably attached to the hip-strap direct.

The appearance of the device is neat, and the sockets, having enlarged outer ends which receive the leather covering of the rods C C as well as the ends of the said rods, protect the ends of the said leather coverings and prevent the stitching from raveling.

Having thus described my invention, I claim and desire to secure by Letters Patent of the United States—

In a breeching-stay for harness, the combination of a central buckle-plate having diagonally-extending sockets at its lower corners, said sockets being screw-threaded at their inner ends and provided with enlarged outer ends, a D-shaped link having an upwardly-extending screw-threaded socket enlarged at its outer end, a D-plate having an upwardly-extending screw-threaded socket enlarged at its outer end, and the curved metallic stay-rods having leather coverings, the ends of which enter the sockets of the buckle-plate, the D-link, and the D-plate, substantially as and for the purpose set forth.

In testimony that I claim the foregoing as my own I have hereunto affixed my signature in presence of two witnesses.

HERSCHEL A. PRICKETT.
